COMBINED FOOD AND BEVERAGE VENDING STATION

Louis A. Zon, Buffalo, N. Y.

Application October 14, 1953, Serial No. 27,179

Term of patent 14 years

(Cl. D13—1)

To all whom it may concern:

Be it known that I, Louis A. Zon, a citizen of the United States of America, and residing at Buffalo, in the county of Erie and State of New York, have invented a new, original, and ornamental Design for a Combined Food and Beverage Vending Station, of which the following is a specification, reference being had to the accompanying drawing, forming part thereof.

Fig. 1 is a top plan view of a combined food and beverage vending station embodying my new design.

Fig. 2 is a front elevational view; the appearance of the side of the lower portion looking in the direction of either the arrow 3 or 4 of Fig. 1, is identical to the side shown.

Fig. 3 is an elevational view of the top portion looking in the direction of the arrow 3 of Figure 1; and

Fig. 4 is an elevational view of the top portion looking in the direction of the arrow 4 of Figure 1.

I claim:

The ornamental design for a combined food and beverage vending station, substantially as shown.
